UNITED STATES PATENT OFFICE.

CHARLES J. BARRENPOHL, OF NEW YORK, N. Y.

COMPOUND FOR CLEANING AND POLISHING METALS, PORCELAIN, GLASS, &c.

No. 847,150.

Specification of Letters Patent.

Patented March 12, 1907

Application filed August 13, 1906. Serial No. 330,315.

To all whom it may concern:

Be it known that I, CHARLES J. BARRENPOHL, a citizen of the United States, and a resident of the city of New York, borough of 5 Manhattan, county and State of New York, have invented a new and Improved Compound for Cleaning and Polishing Metals, Porcelain, Glass, &c., of which the following is a full, clear, and exact description.

This invention is an improved compound for cleaning and polishing metals, porcelain, glass, &c., without injury to the same, and giving them a cleaner appearance and a higher luster than has been hitherto obtainable in compositions for this purpose, and, further, to accomplish this with little muscular exertion on the part of the user.

With these and other objects in view the compound consists of sal-soda, water, whit- 20 ing, and ammonia mixed in substantially the following proportions and in the manner outlined:

In one pint of hot water is dissolved four ounces of sal-soda, which is thereafter added 25 to two pounds of whiting mixed with seven pints of cold water. These are thoroughly intermingled by stirring or shaking, after which two ounces of aqua-ammonia is added, twenty-eight per cent. strong.

The compound is now ready for use and is applied to the metal or porcelain surface with a cloth or other device and allowed to dry, the ammonia acting to hasten drying action, for which purpose it is added. When thoroughly dry, the compound is removed by a clean cloth, leaving the surface to which it was applied clear and with a high polish.

In order to accomplish the best results, the proportion of the ingredients as hereinbefore indicated should be employed. It is, however, evident that they may be slightly varied without departing from the spirit of my invention or sacrificing any of the advantages thereof.

Having thus described my invention, I claim as new and desire to secure by Letters Patent—

The herein-described compound for cleaning and polishing, consisting solely of sal-soda, water, ammonia and whiting.

In testimony whereof I have signed my name to this specification in the presence of two subscribing witnesses.

CHARLES J. BARRENPOHL.

Witnesses:
